To all whom it may concern:

Be it known that I, Nathaniel D. Grasty, a citizen of the United States, residing at Baltimore, State of Maryland, have invented a new, original, and ornamental Design for a Preserving Jar, of which the following is a specification, reference being had to the accompanying drawing, forming a part thereof.

Figure 1 is a top plan view of a preserving jar showing my new design, and

The dominant feature of the present design

consists in the ornamentation of a square container having a squat body, with two motifs arranged on each face adjacent the corner lines of the face, each motif consisting of an elongated projection and inwardly spaced projections, each respectively shorter than the next adjacent projection, the lower ends of each three projections terminating adjacent the bottom of the container.

I claim:
